United States Patent Office.

GEORGE ATKINS, OF SHARON, PENNSYLVANIA.

Letters Patent No. 92,505, dated July 13, 1869.

IMPROVEMENT IN BLAST-FURNACES.

The Schedule referred to in these Letters Patent and making part of the same.

To all whom it may concern:

Be it known that I, GEORGE ATKINS, of Sharon, in the county of Mercer, and State of Pennsylvania, have invented a new and improved Blast-Furnace; and I do hereby declare that the following is a full, clear, and exact description thereof, which will enable others skilled in the art to make and use the same, reference being had to the accompanying drawing, forming part of this specification, in which—

Figure 1 represents a vertical central section of my improved blast-furnace.

Figure 2 is a horizontal section of the same, the plane of section being indicated by the line $z z$, fig. 1.

Similar letters of reference indicate corresponding parts.

This invention has for its object, to so construct a blast-furnace that the waste gases, escaping from the ore or fuel, may be utilized, and carried back to the ore, together with steam, hot air, or superheated steam.

The invention consists in the arrangement of gas-pipes, which lead from the upper part of the furnace down to the tuyeres, through which the blast is injected. Through these pipes, the escaping gases are conducted downward into the lower part of the furnace, where their heat and carbon may be utilized, while they pass up through the ore.

A, in the drawing, represents the chamber of the furnace.

B B are gas-pipes, leading from the upper part of the chamber to tuyeres $a a$, that enter the lower part

of the same, the pipes B being on the outside of the furnace, as shown.

C C are pipes, leading from a steam-boiler, or fan-apparatus, into the tuyeres, and carrying steam, superheated steam, or hot air, into the furnace.

The pipes C may be carried up in the pipes B, and then down again, to superheat the gases that pass through the pipes B.

The gases that escape from the ore will, when the upper damper D is more or less closed, enter the pipes B, and thence through the tuyeres into the lower part of the furnace. They become mixed with the blast in the tuyeres, and, as they are forced into the furnace, a suction is produced in the pipes B, whereby further gases are drawn into the same from above.

The ashes carried into the pipes B, by the gases, are collected in the lower ends of said pipes, which project below the tuyeres, as shown.

Having thus described my invention,

What I claim as new, and desire to secure by Letters Patent, is—

A blast-furnace, provided with gas-pipes B, which lead from its upper part into tuyeres a , at the lower part of the furnace, and, with the blast-pipes C, all arranged substantially as described, to utilize the gases that escape from the ore or fuel, as set forth.

GEORGE ATKINS.
